UNITED STATES PATENT OFFICE.

CHARLES STANFORD UPTON, OF NEW YORK, N. Y.

DESIGN FOR A GAS-BURNER.

SPECIFICATION forming part of Design No. 18,721, dated November 6, 1888.

Application filed August 28, 1888. Serial No. 284,022. Term of patent 14 years.

To all whom it may concern:

Be it known that I, CHARLES STANFORD UPTON, a citizen of the United States, residing at New York, in the county and State of New York, have invented and produced a new and original Design for Gas-Burners, of which the following is a specification, reference being had to the accompanying drawing, forming a part thereof, which drawing represents my design in perspective.

The design consists in a cylindrical body, 1, surrounded by a shorter cylindrical part, 2, or chimney-support projecting out beyond the part 1. A flat horizontal portion, 3, unites the portion 2 with a frusto-conical perforated plate or screen, 4, above which rises a cylindrical perforated thimble, 5. Beads 6, 7 are arranged on the bottom of the cylindrical portion 1 and between the latter and the outwardly-projecting portion 2.

The leading feature of my design consists in the shape of the gas-burner, comprising the cylindrical part 1, the chimney-support 2, projecting out over it, the inclined part 4 over the chimney-support, and the cylindrical part 5 over such inclined or frusto-conical portion; also, in the surface ornamentation, which consists in the perforations in the parts 1, 4, and 5.

What I claim is—

A design for a gas-burner, comprising the cylindrical part 1, the chimney-support 2, projecting out over it, inclined part 4 over the chimney-support, and the cylindrical part 5 over such inclined portion, the parts 1, 4, and 5 having surface ornamentations consisting of 35 perforations, as described and shown.

CHARLES STANFORD UPTON.
